PRECISION OIL HEATER

William T. Foley, Terrace Park, Ohio

Application November 30, 1945, Serial No. 632,038

8 Claims. (Cl. 237—8)

1

The present invention relates to heating apparatus for various purposes wherein precision temperature control is necessary or desirable and has for an object the provision of apparatus that is safe and economical to operate and that is furthermore very compact, and relatively inexpensive of construction.

Another object of the invention is to provide an atmospheric pressure oil heater having the aforementioned advantages and which is free of the hazards of known oil heaters.

Still another object of the invention is to provide an oil heater having an enlarged field of utility and adapted to exceptional nicety of temperature control.

These and other objects are attained by the means described herein and exemplified in the accompanying drawings, in which:

Fig. 1 is a somewhat schematic elevational view of apparatus embodying the invention, operatively connected with a pressing machine, parts being broken away.

Fig. 2 is a cross-sectional view taken on line 2—2 of Fig. 1.

Fig. 3 is a cross-sectional view taken on line 3—3 of Fig. 2.

It is known that oil of high flash test has advantages over water, air or steam as a circulating heat exchange medium but the adoption thereof to precision heating equipment has been very limited because of the requirement for expensive high pressure apparatus and because of the explosion and fire hazards that accompany the use of heretofore known oil heater devices. The troublesome factor has been the difficultly controlled foaming of the circulating oil when water or condensation products are present. The prior known practice for controlling this trouble source has been to employ a closed system capable of withstanding high internal pressures that occur therein. Any leak in such a system permits the escape of a highly flammable and explosive mixture so that very limited fields of application are open to oil heaters as heretofore known.

By the means of the present invention I have found that tranquil and safe operation of an oil heater device can be carried on under atmospheric conditions and that the control of the temperature is more nearly constant than has previously been attained. Thus I am enabled to utilize all of the advantages of oil heating apparatus with any readily controllable kind of firing equipment and without many of the limitations attending various heating apparatus now commonly employed.

In adapting the invention to an oil heater apparatus I have found that the presence of moisture in the oil which is the source of the troublesome foaming cannot be completely elimi-

2

nated but that the foaming action can nevertheless be avoided by a simple and inexpensive means for preventing moisture condensation from re-entering the body of hot oil at the critical area which I have found to be the top surface of the heated oil. Incidentally the moisture initially present in the motor oil that forms the circulating heating medium and any other moisture which may otherwise occur in the medium is at all times allowed to separate from the oil as vapor when the oil reaches a temperature of 212° F. or higher, and is automatically trapped, condensed and removed from the critical zone and the heating is thus carried on with great tranquility. As a result the heat control by inexpensive thermostatic apparatus is exceedingly responsive and where it is desired the required temperature is maintained constantly within 0.5° F. or possibly a lesser variation from demand temperature at which a system embodying the invention is set.

The ensuing description sets forth the invention in connection with a simple pressing machine by way of readily understandable example and not of limitation, and it will be understood by those versed in the art that various modifications will be utilized within the scope of this invention in adapting the same in workmanlike manner for use in different kinds and sizes of precision heating systems for a wide variety of purposes.

In its general aspects the invention consists in providing an oil heater tank or chamber with any suitable firing mechanism that is subject to ready or automatic control, venting the oil tank or chamber to the atmosphere, providing a vapor trap within the tank above the level of the oil therein and pumping the heated oil at low pressure through a hot supply line and a return line to and from the heat utilizing machine, instrument or apparatus of whatever description.

In the drawings a simple compact oil heater tank or chamber 5 may have its bottom 6 and its sidewalls 7 and 8 formed of an integral metal sheet to which suitable mounting brackets or supports 9 and 10 are attached as by welding (not detailed). A front wall 11 and a rear wall 12 are connected to body 6, 7, and 8 to form an oil tight heating tank or chamber for containing a body of motor oil 13 which may be of the Pennsylvania type having a high flash point of say 550° F.

The top level of the oil 13 is located at a distance below the top wall 14 of the tank, which wall may comprise a flanged sheet of metal welded or otherwise secured adjacent the top edges of walls 7, 8, 11 and 12 of the tank.

The heater tank 5 is herein illustrated as an automatic gas fired apparatus and it has secured to its back wall 12 a sheet metal flue chest mem-

ber 15 closed along the top, bottom and sides by integral flanged wall sections 16 which in this case are welded to the exterior face of back wall 12. Gas firing tubes 17 traverse the tank 5 near the bottom and extend through front wall 11 and rear wall 12 and open into the lower portion of chest 15 at a distance below a transverse baffle 18 in said chest. Entered into the front ends of the firing tubes 17 are gas burners 19, desirably of Bunsen type, which are supplied with gas from gas line 20 under the control of an electric gas valve 21 of suitable description, for example as shown in United States Patent No. 1,678,202. Flame and hot products of combustion pass through the firing tubes 17 into the lower flue chest compartment 180 below the baffle 18 from whence they pass through a plurality of heater flue tubes 22 which extend from the upper portion of compartment 180, through the body of oil 13 forwardly into the lower part of a compartment 23 on the front wall 11 of the tank. From the upper part of compartment 23 an upper series of heater flue tubes 24 extend rearwardly through the oil 13 and communicate with the flue chest 15 in the upper compartment 25 thereof which has a stack pipe connection 26 at or near its top. The total heat exchange surface of tubes 17, 22, and 24 exposed on the inner side to flame and hot products of combustion and on the outer side to the oil affords a rapid and efficient heat transfer, the speed of which is in any event at least twice as fast as that of any of the other media such as water or air heretofore used. It is noteworthy that this exceptional capacity of motor oil to quickly take up and yield up large amounts of heat with great speed has been the sole justification for its use in the heretofore known dangerous high pressure systems.

It should now be noted that the following simple vapor trap and vent arranged in the top interior of tank 5 above the oil 13 effectively prevents the heretofore mentioned wild foaming of the oil and by so doing affords a previously unknown degree of accurate heat control using very simple thermostatic devices if desired for the purpose.

I provide a vent pipe 27 in the central part of the top wall 14 of the tank so that moisture in the oil 13 may vaporize and freely separate from the oil as vapor and rise to said vent 27 wherein it may condense and drop. Suspended from the inner or bottom face of top wall 14 and below the vent 27 by means of brackets 28 is a large shallow drip baffle 29 formed like a hollow inverted pyramid with its edges spaced from the inner side wall and top wall of the tank to leave ample flow space around it through which the hot moisture vapors may flow to vent 27. The vent 27 serves as a condenser which directs the condensate into the drip baffle 29 from whence it flows through a drain pipe 30 to the exterior of the tank. I have found that the violent foaming of heated oil has been caused by relatively cold condensate falling on the top surface of the hot oil and that the ability to maintain a temperature constant or in other words precision temperature control is practically lost under conditions of heavy foaming.

I therefore am able to employ the simplest types of thermostatic controls and obtain therefrom surprisingly accurate and almost uniform selected temperatures at the point of use.

In the device of Fig. 1, for example I heat the pressor head of a pressing machine 31 using a hot oil supply line 32 which is fed with oil at a

suitable rate and at low pressure from an electrically driven pump 33 which in this case is turned on and shut off by means of a manually operable switch 34 in known manner. The return flow is by way of pipe 35 which leads from the discharge side of machine 31 to tank 5 in the vicinity of firing tubes 17.

The automatic gas firing equipment including burners 19 with pilot lighters or other igniters (not detailed) and the electrically actuated gas flow valve 21 may be of any suitable designs such as are commonly found in the open markets.

The electrically actuated gas valve 21, a high limit safety thermostat 36 and an adjustable tank temperature thermostat 37 are connected in series in an electrical circuit as by wire 38, 39, 40 and 41 in known manner.

Adjustable tank thermostat 37 may be arranged to open or close the electrical circuit under temperature changes of 1° F., or more or less depending upon the nicety of control required or needed. This thermostat 37 is desirably located closely adjacent the oil intake end of the pump so that the temperature of oil entering the pump will be known to be of the temperature for which the thermostat is set ± 0.5 ° F. The heat loss in pipe 32 regardless of its length can be accurately calculated or it may be determined empirically. The sum of this heat loss in degrees F. plus the desired temperature in degrees F. wanted in the machine 31 will be the amount for which thermostat 37 is set. The high limit thermostat 36 will be set at some higher temperature which is well below the flash point temperature of the oil 13 and operates to automatically de-energize the electric gas valve control and shut off the gas supply in the event temperature control thermostat 37 should fail. The general arrangement just described will serve efficiently for such equipment and instruments as laundry machines, pressers, vulcanizers and many types of heating and molding presses etc. A fine degree of temperature control and safe care free and economical operation are a few of the combined advantages realized.

It will be understood that in automatic space heaters, hot air house heating systems and in kindred apparatus the customary air moving fan and an oil heated radiator may be arranged with safety and convenience in any location with or without air duct systems. The pump and fan employed in such heating systems would be under separate thermostatic control, as under the control of a room thermostat instead of the manual control of the generally corresponding pump 33 of Fig. 1. A delayed action switch for the fan would sometimes be indicated so the starting of the fan may lag a few seconds after the starting of the pump in known manner. The general practices of the heating engineer for meeting various problems are now well established and widely understood. In adapting the precision oil heaters of the present invention those practices are simplified in obvious manner because of the compactness and ready adaptability of the devices.

The necessity for skilled supervision, inspection and licensed operators is obviated since the hazards and dangers involved are not greater than those attending the well-known corresponding fired domestic house heating equipment. The devices of the invention may be fired by means of oil burners or coal stokers or other readily controlled firing apparatus, the mode of adapting any of these being obviously quite similar to the herein described gas firing mechanism.

What is claimed is:

1. An atmospheric pressure precision oil heater system comprising the combination with an instrumentality to be heated, of an oil heater tank vented at its top to the atmosphere, a body of high flash point motor oil in the tank, a condensation baffle in the tank above the oil level and beneath the vent in the top thereof, means to drain the baffle to the exterior of the tank, means to heat the oil below the top surface thereof, thermostatically responsive means extending into the oil and controlling the heating means, a low pressure pump having its intake adjacent said thermostatically responsive member and adapted for circulating the oil at selected rate to a heat utilizing means and a return flow pipe connected to the tank below the pump intake and adapted for connection with the heat utilizing means.

2. An atmospheric pressure precision oil heating apparatus comprising an oil tank having a vent pipe at the top, a drip baffle spacedly mounted within the tank beneath the vent pipe, a body of high flash point motor oil in said tank and having its top surface level below said baffle, a drain tube connecting said baffle with the exterior of the tank, firing means including flue heater tubes traversing the body of motor oil in the tank, electrical means for controlling said firing means, thermostatically responsive electric switching means arranged and adapted in electrical series with said electrical firing control means to control said firing means in accordance with the temperature of said oil at a predetermined level in the tank, and an oil circulating pipe system including an independently controlled low pressure pump, said pump having its intake disposed closely adjacent the said thermostatically responsive means in the tank.

3. An atmospheric pressure oil heater device comprising an oil tank, a body of high flash point motor oil partially filling the tank and adapted for circulation from said tank and return thereto as a heating medium, means to heat oil in the tank, a vent pipe in the top of the oil tank leading unrestrictedly to atmosphere, a drip baffle beneath the vent and traversing a portion of the interior of the tank above the oil level and draining exteriorly of the tank, and means including oil supply and return pipes and a low pressure pump whereby heated oil may be circulated to and from apparatus to be heated.

4. In an oil heating apparatus the combination of a tank having at its top a vent for the exit of vapors to atmosphere, a drip baffle spaced from the top of the tank directly beneath the vent and having its edges spaced from the inside faces of the sidewalls of the tank, a drain tube connecting the said drip baffle with the exterior of the tank, a body of high flash point motor oil in the tank extending to a predetermined level below said baffle, a firing device for heating the oil in the tank to selected temperature, a thermostatically responsive member extending into the body of oil arranged and adapted to control the firing device and means including a low pressure pump connected to the tank for establishing a hot oil flow circuit to and from a device to be heated.

5. Oil heating apparatus comprising a tank having high flash point motor oil partially filling it, firing apparatus to heat the oil in the tank to selected temperature, a thermostatically responsive member extending into the body of oil arranged and adapted to control operation of the

firing apparatus, means including a low pressure pump having its intake disposed adjacent the thermostatically responsive member and oil flow pipes for moving heated oil from the tank to a remote device to be heated and return and means to preclude foaming of the oil in the tank including a vent in the top of the tank for removing moisture vapors to atmosphere and a drip baffle beneath said vent and having a drain to the exterior of the tank.

6. In an atmospheric pressure precision heating system the combination of an oil tank, high flash point motor oil partially filling the tank, means for venting moisture vapors liberated from said oil unimpededly to atmosphere and for diverting incidental condensate therefrom exteriorly of the tank, an adjustable thermostat responsive to the temperature of said oil at a predetermined level therein, firing means for heating said oil and operable under the control of said thermostat and means including a pump for selectively circulating the oil at substantially constant temperature from said tank to a utilizing apparatus and back to said tank.

7. An atmospheric pressure precision heater apparatus comprising a tank having a pipe in the top venting to atmosphere, a drip baffle in the tank beneath the vent pipe and spaced from the interior of the tank, a body of high flash point motor oil in said tank and having its top surface level below said baffle, a drain tube connecting the baffle with the exterior of the tank, heating means traversing the body of oil in the tank, a thermostatically responsive element extending into said body of oil in said tank at a predetermined level arranged and adapted to control the heating means, and an oil circulating pipe system including an independently controlled low pressure pump having its inlet disposed above and closely adjacent said thermostatically responsive element, the system having a return flow connection with the tank below said thermostatically responsive element.

8. An atmospheric pressure heater apparatus comprising a tank, a body of high flash point motor oil partially filling it, a vent pipe leading unobstructedly to atmosphere from the top of the tank, means including a low pressure pump having its intake intermediate the top and bottom of said body of oil for circulating heated oil from the tank to a heat utilizing device and return, and means to preclude foaming of the oil in the tank including a drip baffle interiorly of the tank beneath said vent and arranged to drain exteriorly of the tank.
